UNITED STATES PATENT OFFICE.

EMIL O. ERICKSON, OF LAKE PARK, MINNESOTA.

BOLT-CUTTER.

1,055,970.

Specification of Letters Patent.

Patented Mar. 11, 1913.

Application filed October 22, 1912. Serial No. 727,183.

To all whom it may concern:

Be it known that I, EMIL O. ERICKSON, a citizen of the United States, residing at Lake Park, in the county of Becker and 5 State of Minnesota, have invented new and useful Improvements in Bolt-Cutters, of which the following is a specification.

This invention relates to a device for cutting pipes, bolts, or shafting, the primary 10 object thereof being to provide a tool of this character which will be simple in construction, strong and durable and one which will include radial cutting elements that are adapted to be adjusted relatively as the cutting 15 operation continues and as the diameter of the work is reduced, means being provided to operate so as to simultaneously adjust and hold all of the cutting elements in operative adjusted positions.

20 In the drawing forming a portion of this application, and in which like letters of reference indicate similar parts in the several views:—Figure 1 is a side view of the cutter. Fig. 2 is an edge view thereof. Fig. 25 3 is a section on line 3—3 of Fig. 2. Fig. 4 is a view similar to Fig. 3 showing a slightly modified form of the invention. Fig. 5 is a section on line 5—5 of Fig. 4.

The cutter comprises a support 1 which 30 is preferably of circular configuration and provided with a central work receiving opening 2 and radial openings 3 whose inner ends are in communication with the work opening 2 as shown.

35 The cutting elements 6 of the tool are preferably of rectangular configuration transversely as shown in Fig. 2, the openings 3 in the body member being correspondingly formed and adapted to receive said 40 elements and to hold the latter against rotation as is evident. The cutting extremities 7 of the elements 6 are pointed for effective cutting engagement with the work and as shown said extremities are extended 45 into the work opening 2 whereby to be positively presented to the work.

A combined adjusting and retaining ring 8 is mounted for circumferential movement around the body member 1, being fitted between 50 the companion series of lugs 4 and 5 and provided with actuating extensions 9 of substantially cam formation, being provided with inner surfaces 10 which are substantially tangentially disposed with relation to 55 the body member and adapted to slide across and co-act with similar surfaces 11 of the

slots 12 in the outer ends of the cutting elements 6. A screw 14 carried by the ring 8 is adapted to be engaged with the support 1, so as to hold the ring in any required ad- 60 justed position. Actuating handles 16 extend radially from the ring and are adapted to be manipulated whereby adjustment of the cutting elements 6 can be readily made through their mutual engagement with the 65 extensions 9 of the ring. Similar handles 17^a extend from the body member 1 whereby the tool can be manually rotated upon the work.

In the modified form of the invention 70 shown in Figs. 4 and 5 the cutting element 17 is slidable in the radial opening 18 in a body member 19 and provided with an elongated slot 20 which receives a pin 21, the latter being secured in the walls of the opening 18 and disposed with such relation to the opposite end walls of the slot 20 as to engage the same and to thereby limit the adjustment of the cutting element and hold the element against accidental displacement 75 from the body member. The beveled outer surface 22 of the cutting element extends into a circumferential groove 23 in the body member. The adjusting ring 24 is movable circumferentially of the body member and 80 provided with a projection 25 which extends into the groove 23 and provided with a beveled actuating surface which is adapted to travel over the hereinbefore described surface 22 of the cutting element and thereby 85 move the effective cutting end of said element into the work opening of the body member. A clamping screw 26 on the adjusting band 24 is adapted to engage against the body member whereby the ring will be 90 retained in its adjusted position.

I claim:

1. In cutting mechanism, a work receiving body portion having a central passage and radially movable cutters having their 100 effective cutting points extending into the opening, a ring embracing the body portion and having angularly-disposed portions movable across the cutters and operable to project the effective cutting points of said 105 cutters into the opening when the ring is rotated in one direction, and means for holding the ring in an adjusted position.

2. In cutting mechanism, a work receiving member having a central opening, cutters mounted for radial movement in said member and having their effective cutting 110

points extending into the opening, and a ring adjustable circumferentially of the member and having cutter advancing portions disposed angularly of the cutters and 5 adapted for direct radial contact therewith and operable when the ring is rotated in one direction to advance the cutters into said opening.

3. In cutting mechanism, a work receiving body portion having a central passage 10 and radially movable cutters having their effective cutting points extending into the opening, a ring embracing the member and having angularly-disposed portions movable 15 across the cutters and operable to project

the effective cutting points of said cutters into the opening when the ring is rotated in one direction, means for holding the ring in an adjusted position, a manipulating portion extending radially of the ring, and 20 means carried by the ring and adapted to engage with the member whereby to hold the latter and the ring against relative rotation.

In testimony whereof I affix my signature 25 in presence of two witnesses.

EMIL O. ERICKSON.
